INVENTOR,
Charles W. Ball,
BY *David S. Lain,*
ATTORNEY.

UNITED STATES PATENT OFFICE

CHARLES W. BALL, OF BELLINGHAM, WASHINGTON

CLOTHES WASHING DEVICE

Application filed November 9, 1931. Serial No. 573,811.

My invention relates to improvements in clothes washing devices and has for an object to provide a clothes washer in which the desired movements of the clothes therein is caused by compressed air introduced in the water beneath the clothes.

Another object of my improvement is to provide a tightly closable container of suitable shape for the air method of clothes agitation.

Another object of my improvement is to provide means for disposing of air and other vapors from the washer exterior to the wash room.

Other objects of my improvement will appear as the description proceeds.

I attain these and other objects of my improvement with the device illustrated in the accompanying sheet of drawing in which

Figure 1 is a front elevation of my washing device and Fig. 2 is a side elevation thereof.

Similar characters refer to similar parts throughout. Certain parts are broken away to show other parts hidden thereby.

With more particular reference to the designated parts: The container is, for convenience, made in two parts, the lower part 3 and upper part 4 joined in water-tight connection at central flanges 5. Preferably, parts

3 and 4 are conical in shape with their bases fastened together. Waste pipe 6 is connected to the lower end of cone 3 the outlet from which is covered by screen 9. In pipe 6 is the water trap 7, and the other end of said pipe

leads into a waste water receptacle, not shown.

Gate valve 8 controlled by handle *a*8 is included in the pipe 6 between the cone and trap 7. Vent pipe 10 is connected with the vertex of the cone 4, turns downward to join

pipe 6 with which it is connected above the water trap 7. Hot and cold water pipes 11 and 12, respectively, lead from sources of hot and cold water into the container, preferably closely beneath flange 5. Door frame 13

is tightly fastened to the upper cone 4 and provides a door casing with a plane door jamb against which may be tightly closed hinged door 14 which is provided with the pivoted screw fastening bolt 15. Compressed air pipe

16 leads from a source of compressed air, not

shown, into the lower end of cone 3 above and adjacent screen 9. The interior end 17 of the air pipe, preferably, is bent upward and inclined to one side as clearly shown in Fig. 2.

The ends of hot and cold water pipes 11 and 12, preferably, are bent downward within the container, as shown in Fig. 1 and they are retained closely against the container wall where they enter the same.

In operation: The clothing to be washed is placed in the container through opened door 14 and rests in the lower end of cone 3 on top of air pipe 17. Water of the desired

temperature is allowed to enter the container through pipes 11 and 12 to the desired quantity, gate valve 8 having been first closed.

Soap and washing fluids as desired are placed with the clothing and door 14 is tightly closed. Air under moderate pressure is caused to enter the container through pipe 16. In practice the outlet pipe of a vacuum carpet sweeper has been used with success to supply compressed air to the washer from the fan there-

of when connected with said pipe 16.

Air under pressure entering through upturned pipe end 17 beneath the clothing in the water and at the bottom thereof causes the clothing to rise in the washer and tosses the same about therein producing sufficient agitation thereof, without bringing destructive strains to bear thereon, to quickly bring the cleansing solution in contact with all parts of the clothing for the removal of foreign matter therefrom.

The clothes washing step having been com-

pleted, gate valve 8 is opened and the dirty suds passes through screen 9 into pipe 6 and to the drain to which said pipe leads. Valve 8 is then closed and rinsing water is placed

in the washer through pipes 11 and 12 and compressed air is again introduced through pipe 16 and allowed to agitate the clothing until said clothing has been rinsed to the extent possible thereby. Usually several such

rinsings are required to thoroughly free the clothing from extraneous matter, the water for the same being introduced following the removal of the rinse water preceding. Complete rinsing having been attained, the washing is complete, and the door 14 is unfastened

and opened and the clothing removed by hand from the washer therethrough.

During the washing process, while air under pressure is entering the washer through pipe 16, said air passes upward through the water and enters the upper end of vent pipe 10, passes downward therethrough and enters waste pipe 6 beneath closed valve 8 and above trap 7. The waste air under pressure and mixed with steam and odors of the wash forces itself through the water in trap 7 and escapes into the drain with which pipe 6 is connected.

In practice this washer has done thorough washing with no mechanism other than that required to provide the compressed air and with the entire absence of odors from the clothes being washed.

Having thus disclosed my invention, what I claim as new therein and desire to secure by Letters Patent is,—

1. A clothes washing device including a closable liquid container, an outlet pipe connected with the bottom of said container, a valve in said outlet pipe, a vent pipe connecting the top of said container with said outlet pipe beneath said valve therein, and a compressed-air pipe entering said container at the bottom thereof.
2. A clothes washing machine including a closable liquid container having a tapering bottom, an outlet pipe from the bottom of said container, a valve in said outlet pipe, a screen over the inlet to said outlet pipe, a vent pipe connecting the top of said container with said outlet pipe beneath said valve therein, water pipes connected with said container, and a compressed-air pipe connected with said container at the bottom thereof.
